UNITED STATES PATENT OFFICE.

JAMES ROCHE, OF TERRYVILLE, CONNECTICUT, ASSIGNOR TO THE EAGLE
LOCK COMPANY, OF SAME PLACE.

LOCK.

SPECIFICATION forming part of Letters Patent No. 392,136, dated October 30, 1888.

Application filed May 7, 1888. Serial No. 273,054. (Model.)

To all whom it may concern:

Be it known that I, JAMES ROCHE, of Terryville, in the county of Litchfield and State of Connecticut, have invented a new Improvement 5 in Locks; and I do hereby declare the following, when taken in connection with accompanying drawings and the letters of reference marked thereon, to be a full, clear, and exact description of the same, and which said drawings constitute part of this specification, and represent, in—

Figure 1, a front view of the lock complete; Fig. 2, a vertical transverse section through the lock, showing it as applied to a front, the 15 section cutting through the escutcheon; Fig. 3, a side view of the key; Fig. 4, a longitudinal vertical section cutting through the case and through the key-guide forward of the tumblers; Fig. 5, a front view of the escutcheon; Fig. 6, a longitudinal central section; Fig. 7, a perspective view of the escutcheon-socket detached.

This invention relates to an improvement in that class of locks which are adapted for various uses—such as drawers, trunks, chests, small doors, and cabinet purposes generally—in fact for all locks which are constructed with a “center” or “key-guide” supported in bearings in the case, and which center is adapted 25 to receive the key, and so that the key inserted into the center the center rotates with the key as a guide and support for the key. This center or key-guide is usually arranged in a tube projecting from the front face of the lock, and 30 so that the tube forms a bearing or support for the front or outer end of the center or key-guide. The thicknesses of doors, drawer-fronts, &c., to which this class of locks is adapted or applied necessarily vary to a great 35 extent, and it is necessary that the face or front shall present an escutcheon having a key-hole corresponding to the shape of the key. As now generally manufactured, these locks are constructed with the tube varying in length 40 to correspond to the varying thicknesses of the wood or thing to which they are to be attached, thus necessitating a variety of locks to meet the requirements of the trade, and this variety dealers are compelled to carry. In 45 some cases the tube is made adjustable as to

length, so as to adapt it to various thicknesses; but this adds so much to the expense of manufacture as to make such locks impracticable. In this class of locks the key-guide is arranged in a tube projecting from the face of the case, 5 the tube having an internal flange which overlaps the outer end of the key-guide. The key-hole is a flat radial longitudinal slit in the key-guide, which extends through one side of the guide, and in the flange of the tube a notch is 6 formed, with which the key-hole registers when in the proper position for inserting or removing the key. The key is constructed with a notch or shoulder, which, when properly inserted, will coincide with the flange of 6, the socket, and so that in that condition the key and its guide may be rotated; but unless the guide stands in the position so that it opens through the notch in the flange of the tube the key cannot be inserted or removed. 70 The key-guide is liable at any time to be turned out of such registering position with the notch in the flange of the socket. This, under the common construction, is a great annoyance, and it necessitates the bringing of the face of 75 the key-guide to the outside in an exposed condition, where it can be readily inspected to see if the key-hole of the guide is in the proper position for the insertion of the key.

The object of my invention is to provide a 80 device which will positively hold the key-guide in the position for the insertion and removal of the key, and prevent the guide from being turned, except upon the proper introduction of the key, and which object being attained the lock may be constructed with a short tube and the face of the front provided with an escutcheon, through which the key may be inserted, and pass into the tube of the lock with perfect certainty that the key-guide in the 85 tube is in the proper position to receive the key, and thus make a lock which is adapted for all the various thicknesses of wood or thing to which the lock is to be attached, whereby the dealer avoids the necessity of 90 carrying the variety of locks which the usual manufacture requires him to do; and the invention consists, principally, in constructing the key-guide and one or more of the tumblers 95 so that in the normal position of such tumbler 100

will take a holding-bearing upon the key-guide combined with an independent tumbler, *y* which the said holding-tumbler is locked, and which said independent tumbler is actuated by the key as it passes into the tube, so as to disengage such holding-tumbler and permit the tube to rotate.

In illustrating the invention I show it as applied to a chest-lock, which is sufficient to illustrate the application of the invention to this class of locks generally.

A represents the back plate, provided with the usual selvage, *B*.

C represents the cap, which is constructed with a projecting tube, *D*; *E*, the key-guide, the face end *F* of which stands within the tube *D* against the inwardly-turned flange *G*, formed at the outer end of the tube. The inner end of the key-guide rests in a bearing in the back plate, *A*, as clearly seen in Fig. 2, and so that the key-guide may be rotated within the tube, the axis of the tube and key-guide being at right angles to the plane of the back plate, as usual in this class of locks.

H represents the bolt.

a, *b*, *d*, and *e* represent four tumblers; but it will be understood that there may be more or less of the tumblers, as in the usual construction of this class of locks.

The key-guide is constructed with a longitudinal radial slot, *f*, as usual in this class of tubular locks. The flange *G* of the tube *D* is constructed with a notch, *g*, which corresponds in position to the normal position of the key-hole, as represented in Fig. 1, and also as usual in this class of locks, and so that the flat key, such as seen in Fig. 3, may be inserted into the key-hole, and then as the key is turned the key-guide will revolve with it and permit the bit of the key to act upon the tumblers to throw or draw the bolt, as the case may be.

So far as I have described the lock is of common and well-known construction.

To hold the key-guide in its normal position, so that it is always adapted to receive the key, I construct the guide with a flat surface, *h*—say upon its upper side, as here represented—and one of the tumblers—say *d*—is extended, so that in the normal position of the tumbler—that is, when the bolt is completely thrown or drawn—the said tumbler *d* will rest upon the flat surface *h* of the key-guide, and the tendency of the spring of the tumbler will be to throw the key-guide into the position that its flat side will come into line with the corresponding surface of the key-guide holding-tumbler *d*. This serves to locate the key-guide in the proper position to receive the key; but because the tumbler is yielding the key-guide is free to be turned, notwithstanding the bearing of the tumbler thereon. To render this turning of the key-guide impossible, I introduce a locking-tumbler, *I*, hung upon a pivot, *J*, and so as to swing in a plane parallel with the plane of the holding-tumbler *d*. This tumbler *I* is provided with a stump, *k*, projecting from it and into the plane of the

tumbler *d*, and which stump *i* in the normal condition of the tumbler *d* is adapted to engage a corresponding notch, *l*, formed in said tumbler *d*, and so that when so engaged, as seen in Fig. 4, it is impossible to raise the tumbler *d*; hence the key-guide is securely locked in its normal position, and so locked is in position to receive the key. To disengage the tumbler *d*, the tumbler *i* is constructed with an arm, *K*, which projects from its hub below the key-guide, and on the face of this arm is an outwardly and downwardly inclined surface, *L*, which stands in the path of the key as it comes to its position in the key-guide, and so that the bit of the key striking this arm *K* will depress it, as indicated in broken lines, Fig. 4, before the key reaches its working position in the key-guide. This operation turns the tumbler *I*, so as to remove the stump *i* from its engagement with the tumbler *d*, as indicated in broken lines, Fig. 4, and so as to leave that tumbler *d* free to swing in the usual manner, or as do the other tumblers. So long as the key remains in the lock, the interlocking of the key-guide and holding-tumblers is prevented; but as the key is withdrawn from the key-guide, which can only be done when the key-guide is brought to the position that its key-hole registers with the notch in the tube, the tumbler *I* is left free, and under the action of its spring *M* is returned into locking engagement with the tumbler *d*, and the key-guide cannot be rotated or turned out of position until the proper introduction of the key, as before described. Because of thus locking the key-guide in the proper position to receive the key, the key-guide and its tube may be made very short, much less than the thickness of the front *N*, (see Fig. 2,) or to whatever the lock is attached, and then, an escutcheon being placed upon the outer surface corresponding to the key-guide, the key may be introduced through the escutcheon with a perfect certainty that the key-guide within is in proper position to receive the key.

To direct the key with certainty to the key-hole, the outer face of the key-guide is made of funnel shape with the center at the top of the key-hole, as seen in Fig. 2, so that whenever the point of the key may strike upon the face of the key-guide it will be directed to the key-hole.

The escutcheon must necessarily rotate with the key and must correspond to the key-guide. To produce such an escutcheon, I construct an escutcheon-plate, *m*, of larger area than the area of the tube, and so as to cover the hole made through the front to meet the tube of the lock, as seen in Figs. 2 and 5. Through this plate an opening is made, which corresponds substantially to the open face of the tube—that is, the diameter of the opening *n* through the escutcheon-plate *m* corresponds to the internal diameter of the flange *G* of the tube *D*. On the inner surface of the plate *m* a cup-shaped socket, *r*, is formed, the internal diameter of which is larger than the diameter of

the opening *n*, and upon its inner end the socket is constructed with an internal flange, *s*, which corresponds to the flange *G* of the tube *D*, as seen in Fig. 2. This socket is made of 5 cup shape and struck from sheet metal, as seen in Fig. 7, the opening being in the bottom of the cup. Upon the edge of the cup two or more tenons, *t*, are formed, which set through corresponding mortises in the escutcheon-plate 10 *m*, as seen in Fig. 6, so that the tenons being riveted down upon the outside, the socket is made fast to the plate *m*, substantially as if an integral part of it; but before thus securing the socket to the plate *m* the escutcheon *u* is 15 introduced. This escutcheon is simply a flat disk, in diameter corresponding to the internal diameter of the socket *r* and of a thickness corresponding to the distance between the flange *s* of the socket and the escutcheon-plate, 20 as seen in Figs. 2 and 6. The socket and escutcheon thus applied, and the socket secured to the plate, hold the escutcheon *u*, but so that it may rotate freely in the socket. The escutcheon is constructed with a radial key-hole, 25 *w*, corresponding to the key-hole in the key-guide *E*, and the escutcheon-plate is constructed with a notch, *x*, and the flange *s* with a corresponding notch, *y*, the said two notches *x* *y* corresponding in position to the notch *g* of 30 the tube *D*, so that the escutcheon-plate secured to the front the notches *x* *y* will stand in line with the notch *g* of the tube *D*, as represented in Fig. 2, and so that the key introduced through the escutcheon may be passed 35 directly into the key-guide *E*, directed thereto, as before described. This construction makes a firm and strong support for the rotating escutcheon, and one which is peculiarly adapted for my improvement in the lock itself. The 40 interlocking of a single tumbler which bears upon the key-guide is all sufficient to hold the key-guide in place, yet as many tumblers may be thus interlocked as are desirable, it only being essential that the tumbler which interlocks with the key-guide-holding tumbler 45 shall be actuated by the key after the key has entered the key-guide.

I claim—

1. In a lock in which a rotating key-guide 50 with a radial key-hole therein is arranged to receive the key, the combination therewith of a holding-tumbler, the said key-guide constructed with a surface adapted to engage said holding-tumbler when the key-guide is 55 in position to receive the key, and a second tumbler constructed to engage said holding-tumbler when the key-guide is in said normal position, the said second tumbler provided with a bearing-surface over which the key will 60 pass after it enters the key-guide, substantially as described, and whereby the said key in so passing into the key-guide will disengage the said second tumbler from the holding-tumbler.

2. In a lock substantially such as described, 65 the combination of the key-guide *E*, constructed with a radial longitudinal key-hole open-

ing through one side, the said key-guide constructed with a flat surface, *h*, one or more tumblers, *d*, hung in the case to swing in a plane at right angles to the axis of said key-guide and arranged to bear upon said flat surface of the key-guide when the key-guide stands in the position to receive the key, a tumbler, *I*, hung in the case so as to swing in a plane parallel with the holding-tumbler *d*, 70 the said tumbler *I* constructed with a stump, *i*, and the said holding-tumbler with a corresponding notch, the said stump and notch arranged to engage the said tumblers *I* and *d* when the key-guide is in the normal position, 75 and the tumbler *I* constructed with an arm extending therefrom provided with an inclined surface in the path of the key as it enters the key-guide, substantially as described.

3. The combination of a lock having a key-guide, *E*, constructed with a radial longitudinal key-hole adapted to receive the key and so as to rotate with the key, the case of the lock constructed with a tube, *D*, concentric with said key-guide *E*, and within which said 90 key-guide *E* is arranged and so as to rotate therein, the said tube constructed with a flange, *G*, at its outer end overlapping the face of the said key-guide, and the said flange constructed with a notch, *g*, corresponding to 95 the key-hole when the key-guide is in the normal position, an escutcheon consisting of an escutcheon-plate, *m*, having an opening through it corresponding in diameter to the internal diameter of the said flange *G*, and 100 the said opening constructed with a notch, *x*, corresponding to the notch *g* of the flange *G*, the socket *r*, constructed with a flange, *s*, upon its inner edge, the internal diameter of which corresponds to the opening *n* in the plate *m*, 105 and the said flange *s* constructed with a notch, *y*, corresponding to the notch *x* of the opening in the plate *m*, the said socket *r* also constructed with tenons *t*, set through corresponding mortises in the plate *m*, riveted thereon 110 as a means of securing the socket to the plate, with the disk *u* within said socket and between the flange *s* and the plate *m*, the said disk *u* constructed with a radial key-hole, *w*, corresponding to the radial key-hole in the 115 key-guide, substantially as and for the purpose described.

4. In a lock having a rotative key-guide constructed with a longitudinal radial key-hole adapted to receive the key, a tube within 120 which said key-guide rotates, the said tube constructed with an internal flange at its outer end to overlap the face of the said key-guide, and the said flange constructed with a notch corresponding to the said key-hole, the face of 125 the said key-guide constructed of funnel shape, substantially as and for the purpose described.

JAMES ROCHE.
